Primary Examiner — Antoine D Davis(74) *Attorney, Agent, or Firm* — Michael Best & Friedrich LLP**CLAIM**

I claim the ornamental design for a tool interface for an accessory, as shown and described in FIGS. 1-3.

DESCRIPTION

FIG. 1 is a perspective view of a tool interface.

FIG. 2 is a top view of the tool interface shown in FIG. 1; and, FIG. 3 is a bottom view of the tool interface shown in FIG. 1. The broken line showing of the environment is for illustrative purposes only and forms no part of the claimed design. The broken lines which define the boundaries of the claimed design form no part thereof.

The design sought to be patented in FIGS. 1-3 is not visible in the rear, front, left side and right side views. Accordingly, these views have been omitted.
